5 Claims. (CL 105—44)

This invention has for its object to provide improvements in and relating to high powered steam engines, such as locomotives, notably where the boiler pressure is increased.

5 In order to reduce as much as possible wire-drawing losses during the steam admission in high powered steam engines and more particularly in steam locomotives, it is proposed to improve the coefficient of orifice of the steam admission devices.

10 This means that for equal rates of cut off, it is possible to admit a larger volume of steam into the cylinders with this proposed invention, than hitherto was possible by known means of steam distribution.

15 Such results can be obtained by connecting the cylinders and the superheated header by means of an exceptionally large live steam pipe. On account of mechanical considerations, such as smoke box design which must be air tight, as well as the accessibility for cleaning purposes to the boiler tubes, the piping from the superheater header to the cylinders must be kept as small as possible and this means that when these locomotives are operating under heavy loads, the current of steam which passes through these pipings is received at pulsatory speed which corresponds to the events of the cycle of several cylinders.

20 In the case of multiple expansion engines where the steam admission is subdivided into different cycles, the fluctuations due to the intermittent exhaust from the previous stage will also cause pulsations in the received volume. It is therefore also advantageous to interpose between two consecutive stages of expansion such devices in order to render practically impossible the effects of fluctuations of steam pressure on the efficiency of admission into the cylinders.

25 The arrangement according to my invention which remedies above drawbacks, comprises in combination with the high pressure cylinders or low pressure cylinders in case of multiple expansion of a steam locomotive, an intermediate reservoir located between the admission chest of said cylinders and the source of admission steam, which reservoir is in constant communication with said source of steam as well as with the admission valve chests of all the cylinders concerned, with a view to regulate the admission of steam to cylinders, and to keep as constant as possible the pressure of inlet steam.

30 The question of weight having to be given a special consideration in high powered locomotives, said intermediate steam chest or reservoir will have to be made preferably of cast steel instead

of cast iron in order to reduce its weight. On the other hand said reservoir will receive such a shape which best resists heat stresses, such as cylindrical or spherical.

35 The cylindrical reservoir or steam chest located between the cylinders and the source of admission steam, can be arranged with its longitudinal axis parallel to the longitudinal axis of the locomotive, longitudinal webs being arranged parallel to the direction of stresses which webs will thus play the part of re-inforcing the reservoir or steam-chest.

40 Another drawback which is met with in high powered steam locomotives, is that differences of temperature are very high between parts subject to steam contact on said locomotives, so that the stresses caused by the expansion and contraction of those parts due to said differences of temperature, are very material and very often cause injuries in said parts.

45 In order to remedy such drawback, according to my invention, the cylindrical reservoir which constitutes in effect a steam accumulator, is coaxial with the longitudinal axis of the locomotive between all the steam cylinders which are to be fed by this reservoir, the admission in said cylinders being thus effected through the portions of said cylinder castings which are located nearer the locomotive centre, whilst the exhaust is effected on the external portions of said cylinders, thus ensuring a gradual fall of temperature from the locomotive centre to the external portions of said locomotive, cast parts being thus no longer affected by sudden changes of temperature.

50 According to my invention, the exhaust chambers are definitely separated from the live steam chambers, whilst on another hand, the exhaust conduits are given easy curves at the bends, so that they have a stream line shape in order to reduce to the minimum the heat radiation and to transform into velocity the pressure energy of the exhaust steam at the bottom of the blast pipe.

55 In order to reduce as much as possible the back pressure in locomotive cylinders, it is obviously necessary to increase the sectional area of the exhaust organs. Such result may be obtained in the case of poppet valves by simply increasing the diameter of such valves, but this is sometimes not possible since it results in an increase of the distance between valves and corresponding cylinders, which unduly increases the clearance volumes.

60 According to my invention, above drawback is eliminated by locating on every cylinder two or

more exhaust valves, preferably of the poppet valve type, thus securing a sufficient sectional area for the exhaust and also reducing the back pressure in the cylinder, with the minimum of 5 clearance volume.

In order to remedy the difficulty of removing valves, more especially exhaust valves, by reason of the increase of diameter of said valves, due to the carbon deposited on said valves by the 10 exhaust steam, a special aperture is proposed in the exhaust cavity which permits of the decarbonization of the surface of said exhaust valves when same are in place. The exhaust valves can thus be made practically completely balanced as 15 the difference between the diameter of the upper valve seat and the lower valve seat is then made practically nil.

In the accompanying drawings which show by way of example arrangements according to my 20 said invention, applied to a high powered locomotive with poppet valve steam distribution:—

Fig. 1 is a horizontal sectional view on the line 1—1 of Fig. 2 of a block constituted by the engine cylinders and the intermediate reservoir.

Fig. 2 is an end view of Fig. 1 partly in section.

Fig. 3 shows an exhaust valve chamber having an aperture provided with a removable cover.

According to my invention, an intermediate 30 reservoir 1 (Figs. 1 and 2) is located between the cylinders 2 of the steam engine and is conveniently connected with said cylinders so as to constitute a block or unit, said unit being preferably cast in one piece. A passage 3 is provided for 35 connecting said intermediate reservoir 1 with the source of steam not shown in the drawings. Said passage 3 is, in addition, connected with the valve chests or steam admission chambers 4 suitable for the reception of double seat poppet valves 40 7, as shown in Fig. 1.

Owing to the arrangement of said intermediate reservoir 1 which directly communicates with the source of steam not shown in the drawings, through conduit 10, the steam admission chamber 45 4 being, on the other hand, in constant communication with both reservoir 1 through passage 3, and with the source of steam not shown, through the conduit 10, it is clearly seen that as shown by the arrows in Fig. 1, during the 50 operation of the engine, the reservoir 1 acts as an auxiliary source of steam. Owing to the close proximity of the reservoir 1, the steam admission valves 5 receive directly steam from both reservoir 1 and the source of steam not shown in 55 the drawings, through the conduit 10, and are thus permanently surrounded by a very considerable mass of steam. As a result the admission of steam into each cylinder takes place with the same pressure during the whole time of opening 60 of the inlet valve, so that every cylinder of the engine receives exactly the quantity of steam at a pressure which is exactly the figure for which the engine has been designed, thus securing the efficiency which has been predetermined for the 65 locomotive.

As it is well known, in the case for instance of a single expansion engine comprising only two cylinders one of which is located on either side of the locomotive for the convenience of the arrangement of distribution organs, the cylinders tend to be displaced relatively to each other during the operation of the pistons, thus causing additional stresses upon the frame. On the other 70 hand, said cylinders being without any connection between each other, suffer very important

losses of heat which take place inside said cylinders thus causing condensations of steam and a corresponding reduction of efficiency.

Because of the arrangement of the intermediate reservoir between the cylinders, it is possible by 80 casting in a unit said cylinders and said reservoir provided with reinforcing webs 12, to secure great rigidity which absorbs the greater part of the stresses transmitted to same. On the other hand, owing to the arrangement of the reservoir which is always full of admission steam, that is to say with steam at a higher temperature than the temperature existing inside the corresponding cylinders, said reservoir being located between the cylinders, the temperature progressively decreases from the locomotive centre towards the outer portions of cylinders so that said arrangement avoids 85 any sudden changes of temperature, and the cylinders are only subjected to internal stresses.

The exhaust chambers located outside of this unit and without any direct contact with admission chambers, constitute a heat insulation which reduces the losses of heat, so that the condensations of steam inside cylinders are reduced and the efficiency is increased.

Inlet valves 5 are located in the admission chest 4. A passage 6 connects every cylinder 2 with the exhaust pipe through exhaust valves 7. The exhaust cavities are definitely separated from the admission steam cavities and the stream line 106 principle having been adopted in the design of exhaust passages 6, the pressure energy of the exhaust steam is transformed into velocity which increases the velocity of the combustion gases in the lower part of the blast pipe.

According to my invention, every part of the cylinder is provided with two exhaust valves 7 and 8 which are arranged as shown in Figs. 1 and 2, so that while a large sectional area is offered to the passage of exhaust steam, said 110 valves each have a reduced diameter, and each of said valves may thus be arranged close to the cylinder for reducing the volume of clearance spaces, which results in an increase of thermal efficiency of each cylinder while, on the other 115 hand, the back pressure is reduced due to a more regular and complete exhaust.

As shown in Figs. 2 and 3, each exhaust cavity 6 is provided with a special aperture 9 which receives a cover 11. It is thus possible to de-carbonize the surface of the exhaust valves such as 7 and 8 while same are in place. Said exhaust valves in fact are, after a certain time of operation, covered with a layer of carbon constituted by a part of the oil used for the lubrication 125 of the cylinders, and carried away by the exhaust steam. In actual steam engines, in practice, such layer of carbon has very often such an importance and has become so hard that it prevents the removal of balanced double seat 130 valves and it is usual for rendering possible said removal to increase the diameter of the main seat of valves which does not allow said valves to be reasonably balanced.

The arrangement of said aperture 9 with a removable cover 11 allows the exhaust valves to be conveniently decarbonized when still in place, so that it is then possible to easily remove said valves which may thus be practically completely balanced, owing to the difference between the 145 diameter of the upper valve seat and the lower valve seat, being made practically nil.

What I claim is:—

1. In a high powered steam engine, two cylinders, conduits for conducting steam from a boiler 150

directly to said cylinders, a central reservoir between said cylinders connected with and common to the steam conduits of both cylinders, said cylinders and central reservoir comprising a unitary structure of maximum compactness, exhaust conduits, exhaust valves controlling said exhaust conduits, means for preventing the admission steam chambers of said cylinders from being cooled through contact with said exhaust conduits, and means whereby decarbonizing of the surfaces of said exhaust valves may be effected without removing said exhaust valves from their seats.

5. In a high powered steam engine, two cylinders, conduits for conducting steam from a boiler directly to said cylinders, a central cylindrical reservoir between said cylinders connected with said steam conduits, said central reservoir being coaxial with the longitudinal axis of the engine, 80

and in combination with said steam cylinders comprising a unit of maximum compactness, exhaust conduits located exteriorly of said unit and out of direct contact with the admission steam 85

chambers of said cylinders, two twin exhaust poppet valves for each steam cylinder, and means whereby decarbonizing of the surfaces of said exhaust valves may be effected without removing said exhaust valves from their seats.

6. In a high powered steam engine, two cylinders, conduits for conducting steam from a boiler directly to said cylinders, a central cylindrical reservoir between said cylinders connected with said steam conduits, said central reservoir being coaxial with the longitudinal axis of the engine, 90

and in combination with said steam cylinders comprising a unit of maximum compactness, exhaust conduits located exteriorly of said unit and out of direct contact with the admission steam 95

chambers of said cylinders, two twin exhaust poppet valves for each steam cylinder, and means whereby decarbonizing of the surfaces of said exhaust valves may be effected without removing said exhaust valves from their seats.

7. In a high powered steam engine, two cylinders, conduits for conducting steam from a boiler directly to said cylinders, a central cylindrical reservoir between said cylinders connected with said steam conduits, said central reservoir being coaxial with the longitudinal axis of the engine, 100

and in combination with said steam cylinders comprising a unit of maximum compactness, exhaust conduits located exteriorly of said unit and out of direct contact with the admission steam 105

chambers of said cylinders, two twin exhaust poppet valves for each steam cylinder, the wall of each exhaust conduit being provided with an 110

aperture accessible from the outside, a removable cover for each of said apertures for giving access to said exhaust valves when the latter are on their seats and thereby permitting said valves to be decarbonized prior to their removal.
